UNITED STATES PATENT OFFICE.

ALEXANDER W. HESS, OF SAN JOSE, CALIFORNIA, ASSIGNOR TO ANDREW S. WILLIAMS, OF SAN JOSE, CALIFORNIA.

FEED FOR OIL-BURNERS.

SPECIFICATION forming part of Letters Patent No. 742,648, dated October 27, 1903.

Application filed December 24, 1902. Serial No. 136,485. (No model.)

To all whom it may concern:

Be it known that I, ALEXANDER W. HESS, a citizen of the United States, residing at San Jose, in the county of Santa Clara and State of California, have invented new and useful Improvements in Feeds for Oil-Burners, of which the following is a specification.

My invention relates to new and useful improvements in oil-burners especially adapted for use in connection with furnaces, &c., and is more particularly an improvement in valve mechanism whereby steam and oil may be mixed in any proportion and such mixture supplied to the burner in desired quantities.

Another object is to provide means whereby the valves may be operated in unison from a damper-regulator to increase or diminish the size of the flame in the furnace.

With the above and other objects in view the invention consists in the novel construction and arrangement of the several parts, which will be more fully hereinafter described and claimed.

In the drawings, Figure 1 is a front elevation of a furnace having my improved mechanism attached thereto. Fig. 2 is a detail view of the mechanism detached. Fig. 3 is an end elevation of the valves and the arms extending from the stems thereof, the quadrant and the operating mechanism being removed; and Fig. 4 is a plan and edge view of the swinging guide-bar.

Referring to the figures by numerals of reference, 1 is a mixing-chamber or oil-atomizer, one end of which is connected by means of a pipe 2 with a suitable burner arranged within a furnace 3. A pipe 4 opens into the opposite end of this mixing-chamber and serves to conduct steam thereto from a suitable source. A rotary valve 5 is arranged within the pipe 4 adjacent to the mixing-chamber 1 and has an arm 6 extending downward from the stem thereof, said arm being provided with a series of apertures 7 for the reception of a bolt 8, extending through one end of the notched strip 9. An oil-supply pipe 10 is connected to the bottom of the mixing-chamber 1 by means of a pipe 11, and within this pipe is located a valve 12, to the stem of which is secured an arm 13, having a groove 14 in the lower end thereof. This groove is adapt-

ed to receive one edge of a quadrant 15, secured to the front of the furnace, and which serves as a guide for the arm during the movement thereof. A guide-strip 16 is loosely mounted upon the stem 17 of valve 12 and is also grooved at its outer end, as shown at 18, and this groove receives the inner edge of quadrant 15 and is likewise guided thereby. Headed studs 19 extend from opposite sides of the strip 16, and one of these is adapted to engage one of a series of notches formed upon a strip 20, pivoted to arm 13 at a point adjacent to the outer end thereof, while the remaining stud 19 engages the end of a rod 21, pivoted to a bell-crank lever 22, which is connected by means of a rod 23 to a suitable damper-regulator. (Not shown.) The arm 13 extends upwardly a short distance above the stem 17, and a stud 24 extends laterally therefrom and is adapted to engage any one of the recesses formed within the strip 9, before referred to.

In operation a desired quantity of steam is admitted to the mixing-chamber 1 by opening the valve 5, and oil is also admitted thereto, preferably under pressure, by swinging arm 13 toward the guide-strip 16. When this oil-valve 12 has been opened a sufficient distance to admit a desired proportion of oil to the mixing-chamber 1, the notched strip 20 is placed into engagement with its lug 19, and notched strip 9 is likewise placed into engagement with lug 24. The two valves are thus locked together and one cannot be opened or closed without a corresponding movement of the other, and it will thus be seen that the proportion of oil and steam supplied to the mixing-chamber 1 will remain unchanged until one or the other of the strips 9 and 20 is disengaged from its lug and readjusted. By pulling upward upon the rod 21 the two valves may be opened in unison, thereby increasing the quantity of mixed oil and steam supplied to the burner, and the supply will be diminished or cut off when the guide-strip 16 is swung downward. By connecting this guide-strip to the damper-regulator it will be seen that the flame may be so controlled as to produce a uniform heat.

With valve-operating mechanism of this character the proportions of steam and oil in

the combustible-mixture supply to the burner can be readily regulated and a practically smokeless flame produced. By means of the notched strip 20 the guide-strip 16 may be locked in any desired position in relation to arm 13, and in this way the movement of said strip and arm, and obviously of the arm 6, may be increased or diminished, thereby regulating the amount of mixture supplied to the burner.

If desired, the connections between the valve-operating mechanism and the damper-regulator may be dispensed with and the valves opened or closed simultaneously by hand.

In the foregoing description I have shown the preferred form of my invention; but I do not limit myself thereto, as I am aware that modifications may be made therein without departing from the spirit or sacrificing the advantages thereof.

Having thus described the invention, what is claimed as new is—

1. In mechanism of the character described, 25 the combination with a mixing-chamber having steam and oil inlets; of a valve in each of said inlets, a stem projecting from each of the valves, an arm secured to each stem and adapted to operate the valve thereof, an adjustable connection between said arms whereby the valves may be operated in unison, a guide-strip loosely mounted upon one of the stems and adapted to be connected to valve-operating means, and an adjustable connection 35 between said strip and one of the arms.

2. In mechanism of the character described,

the combination with a mixing-chamber having an outlet, steam and oil inlets, and a valve in each of said inlets; of an arm extending from each of said valves, an adjustable connection between said arms whereby the valves may be operated in unison, a fixed quadrant adapted to engage and guide one end of one of the arms, a swinging guide-strip adapted to be connected to valve-operating means and engaging and slidably mounted upon said quadrant, and an adjustable connection between said guide-strip and one of the arms of the valves.

3. In mechanism of the character described, 50 the combination with a mixing-chamber having an outlet, inlets, a valve in each of said inlets, of an arm extending from one of the valves, a notched strip pivoted thereto, a quadrant, an arm extending from the remaining valve and engaging and slidably mounted upon said quadrant, a lug upon the last-mentioned arm adapted to be engaged by the notched strip, a guide-strip loosely mounted upon one of the stems and engaging and slidably mounted upon the quadrant and adapted to be connected to valve-operating means, and a notched strip pivoted to one of the valve-arms and adjustably secured to said guide-strip.

In testimony whereof I affix my signature in presence of two witnesses.

ALEXANDER W. HESS.
